(57) CLAIM

The ornamental design for an iron golf club head, as shown and described.

DESCRIPTION

FIG. 1 is a front view of the iron golf club head of our design; FIG. 2 is an enlarged front view of the highlighted portion of the iron golf club head shown in FIG. 1; FIG. 3 is a perspective view of a portion of the iron golf club head shown in FIG. 2;

FIG. 4 is a rear view thereof;

FIG. 5 is a bottom view thereof;

FIG. 6 is a left side view thereof;

FIG. 7 is a right side view thereof;

FIG. 8 is a front view of a second embodiment of the iron golf club head disclosed in FIG. 1;

FIG. 9 is an enlarged front view of the highlighted portion of the iron golf club head shown in FIG. 8;

FIG. 10 is a perspective view of a portion of the iron golf club head shown in FIG. 9;

FIG. 11 is a rear view thereof;

FIG. 12 is a bottom plan view thereof;

FIG. 13 is a left side view thereof; and,

FIG. 14 is a right side view thereof.

The broken line showing is included for the purpose of illustrating and forms no part of the claimed design.

1 Claim, 8 Drawing Sheets
